United States Patent Office

Des. 185,694

Patented July 21, 1959

185,694

COMBINED TOY ROCKET AND LAUNCHER

Carl Ayala, Chicago, Ill., assignor to Marvin I. Glass,
Chicago, Ill.

Application January 19, 1959, Serial No. 54,207

Term of patent 14 years

(Cl. D34—15)

Fig. 1

Fig. 2

Fig. 3

Fig. 4

Figure 1 is a perspective view of a combined toy rocket and launcher showing my new design;

Figure 2 is a side elevational view;

Figure 3 is a front elevational view; and

Figure 4 is a rear elevational view thereof.

I claim:

The ornamental design for a combined toy rocket and launcher, substantially as shown.
